Frank Breckenridge, Mansfield, Ohio, assignor to
Westinghouse Electric & Manufacturing Com-
pany, a corporation of Pennsylvania

Application December 7, 1938, Serial No. 81,627

Term of patent 7 years

To all whom it may concern:

Be it known that I, Frank Breckenridge, a citizen of the United States, residing at Mansfield, in the county of Richland and State of Ohio, have invented a new, original, and ornamental Design for a Combined Washing Machine and Wringer, of which the following is a specification, reference being had to the accompanying drawing, forming part thereof, in which:

Figure 1 is a perspective view of a combined washing machine and wringer showing my new design; and

Fig. 2 is a top plan view of the combined washing machine and wringer shown in Fig. 1.

I claim:

The ornamental design for a combined washing machine and wringer, substantially as shown.

FRANK BRECKENRIDGE.
